UNITED STATES PATENT OFFICE

2,509,355

INTEGRAL HINGE FOR RECEPTACLE CLOSURES

Edmund P. Kampa, Cedarburg, Wis.

Application February 19, 1945, Serial No. 578,668

1 Claim. (Cl. 220—31)

1

My invention relates to compact constructions and more particularly to a type of compact that is constructed entirely of plastic material.

The object of my invention is to provide a device that may be constructed entirely of plastic material without the use of metal for hinging the cover to the body of the device.

Another object is to provide a compact that is constructed entirely of plastic to which the cover is retained in a closed position due to the resiliency of the material itself.

Still another object of my invention is to provide a device of the character described that has a molded screen of plastic material which frictionally engages the inner walls of the body.

Other and further objects of my invention will become more apparent as the description proceeds when taken in conjunction with the drawings, in which:

Figure 1 is a perspective view of the entire compact in a closed position.

Figure 2 is a cross sectional view of the device taken at the line 2—2, in Figure 1, and showing the cover in a closed position.

Figure 3 is a fragmentary cross sectional view of the device taken at line 3—3, of Figure 1, showing a portion of the cover in an open position.

Figure 4 is a plan view of the body of the device before assembly.

Figure 5 is a fragmentary view of a portion of the cover showing the hinge arrangement integrally molded with the cover.

Figure 6 is a fragmentary view of a portion of the body with the retainer cap in position, and

Figure 7 is a fragmentary, cross sectional view of a portion of the assembled hinge construction illustrating the hinge pin mounted on the bearing member and held in position by the retainer cap.

Similar characters of reference indicate corresponding parts throughout the several views, and referring now to the same the character 10 shows a body of a compact annular in contour and with a cover 11 of a similar contour. Obviously, the shape of the device may be changed to any desired contour, and in no way interferes with its construction or efficiency.

The body 10 is shown provided with a shoulder 12 around its entire inside of the vertical walls, leaving a chamber 13, providing a receptacle for retaining face powder or the like, forming the contents of the compact. The cover 11 is equipped with a flange member 14 extending downward

2

at right angle and engaging the shoulder 12 of the body 10 when the compact is closed.

At the rearward end of the cover 11 is a hinge structure provided with outwardly extending hinge pins 15 molded integral with the cover 11. A mirror 16, supplied as an accessory is disposed within the inner face of the cover 11 as shown.

The body 10 is provided with an elongated depression 17 at its rearward end, and vertical bearing pins 18 extend upward from the bottom of the depression 17 at each end thereof.

Retainer caps 19, molded of the same plastic material and of a semi-annular contour at their tops, are adherently embedded into the ends of the depression 17 over the bearing pins 18, after the cover 11 is placed into position, by engagement of its flange 14 against the shoulder 12 in the vertical walls of the body 10. As the hinge pins 15 are placed in frictional contact with the tops of the bearing pins 18, the retainer caps are inserted and will prevent any sideward or upward movement of the pins 15, thereby providing a hinge construction of the plastic material and having the appearance of an integral structure.

The front of the cover member 11 is provided with an outwardly extending member 20, having a downwardly projecting lip 21 provided with an inwardly extending retaining member 22. This member 20 engages a depressed slot 23 formed into the front face of the body 10 and as the cover 11 is brought down into position the member 22 will snap into a position below the lower face 24 of the body 10 and will be held in position by the resiliency of the plastic material, of which the entire unit is constructed and of which the member 20 is an integral part.

There is a molded screen 25 of plastic material, placed into the chamber 13 of the body 10, to cover the contents of the compact. This screen is provided with a plurality of apertures 26 and frictionally contacts the vertical side walls of the chamber 13 at 27. The screen 25 may be straight, or convex as shown in Figure 3, or may be of a concave contour, as shown in Figure 2. By the user applying pressure on the surface of the screen 25, the contents such as face powder, is forced upward through the apertures 26, to contact with a powder puff or the like. The screen 25 may be constructed of a transparent plastic, if desired, to further enable the user to determine the color of the contents of the compact.

It is manifest to anyone familiar with the art that a device of the character described provides

a very desirable unit in which its entire construction is of a molded plastic material without the use of metal plates or pins which have a tendency to corrode or become loose with wear. Obviously, the unit may be constructed in various shapes, sizes and colors, and the construction of the hinge assembly, having the retaining caps embedded into the depression 17 and retained rigidly by means of a proper adherent agent produces an effective serviceable product. The plastic screen 25 constructed of the same general type of material provides a smooth serviceable surface far superior to a wire screen or cloth, and its one piece construction retains the contents within the chamber of the body without spilling due to its frictional contact with the sides of the chamber.

While I have herein shown a single embodiment of my invention for the purpose of clear disclosure it is to be understood that many changes may be made in the arrangement, size and configuration of the various parts within the scope of the appended claims.

What I claim and desire to secure by Letters Patent in the United States is:

A device of the character described comprising a hollow body portion open at its upper face, said body portion provided with a recess within said upper face, a cover portion open at its lower

face, said cover portion having a hinge member extending therefrom, said hinge member provided with hinge pins extending outward therefrom on both of its ends, the recess within said body portion provided with upwardly extending bearing pins acting as supports for said hinge pins on said cover portion, and a cap member arranged for engagement with the ends of said recess over said hinge pins to retain said hinge pins in direct contact with said bearing pins and acting as a means for covering and totally enclosing the ends of said hinge pin.
